UNITED STATES PATENT OFFICE.

WILLIAM R. EVANS, OF EAGLEVILLE, MISSOURI.

SHADE AND CURTAIN FIXTURE.

No. 835,987.

Specification of Letters Patent. Patented April 28, 1908.

Application filed July 12, 1907. Serial No. 833,453.

To all whom it may concern:

Be it known that I, WILLIAM R. EVANS, a citizen of the United States, residing at Eagleville, in the county of Harrison and State 5 of Missouri, have invented a new and useful Shade and Curtain Fixture, of which the following is a specification.

The invention relates to improvements in shade and curtain fixtures.

10 The object of the present invention is to improve the construction of curtain fixtures, and to provide a simple and efficient curtain fixture, adapted to be cheaply manufactured, and capable of ready adjustment to suit curtains of different widths.

A further object of the invention is to provide a curtain fixture of this character adapted also to form a support for a curtain pole.

With these and other objects in view, the 20 invention consists in the construction and novel combination of parts hereinafter fully described, illustrated in the accompanying drawing, and pointed out in the claims hereto appended; it being understood that various 25 changes in the form, proportion, size and minor details of construction, within the scope of the claims, may be resorted to without departing from the spirit or sacrificing any of the advantages of the invention.

30 In the drawing:—Figure 1 is an elevation of a curtain fixture, constructed in accordance with this invention. Fig. 2 is a plan view of the same. Fig. 3 is a vertical sectional view, taken substantially on the line x—x of Fig. 1. 35 Fig. 4 is a detail perspective view of one of the supports. Fig. 5 is a detail perspective view of one of the bearing brackets.

Like numerals of reference designate corresponding parts in all the figures of the drawing.

40 1 and 2 designate adjustable L-shaped bearing brackets, constructed of stout sheet metal, or other suitable material and each consisting of an outwardly extending bearing arm and a transversely disposed ratchet arm 3. The bearing arm of the bracket 1 is provided with a substantially oblong opening 4 for the reception of the journal 5, which is connected with the spring of a shade roller 50 6, and the opening of the bearing arm of the other bracket is circular to receive the journal 7.

The bearing brackets are mounted in supports 8, constructed of sheet metal, or other 55 suitable material. Each support 8 consists of a substantially oblong piece of sheet metal,

having its ends bent outwardly to form projecting flanges 9, which are set at an inclination, as clearly illustrated in Fig. 1 of the drawing. The inclined outwardly projecting flanges are provided with aligned slots or openings 10 to receive the ratchet arm 3, which is provided at its lower edge with notches 11 for engaging the guide flanges 9 at the bottom of the slots or openings 10. The 60 bearing brackets are adjustable transversely of a window to space the bearing arms different distances apart to accommodate curtains or window shades of different widths.

Each support 8 is provided at a point intermediate of the guide flanges with an outwardly bowed downwardly tapered portion 13, forming a downwardly tapered socket 14 for the reception of a curtain pole bracket 15. The body of the support 8 is perforated at 70 opposite sides of the intermediate bowed portion to receive screws for securing it to a window frame or casing, and when the supports are applied to a window frame or casing, as illustrated in Figs. 1 and 2 of the 80 drawing, the curtain pole brackets may be fitted in the sockets 14, and they will be clamped therein by the downward taper of the said sockets. The tapering of the sockets operates to set the guide flanges 9 at 85 an inclination, as more metal is required for the formation of the upper portion of the socket than the lower portion thereof. The curtain pole supports, which may be readily removed from the sockets, when desired, 90 have outwardly extending portions, located above the curtain or window shade and provided at their outer ends with suitable seats 16 for the reception of a curtain pole.

Having thus fully described my invention, 95 what I claim as new and desire to secure by Letters Patent, is:—

1. A curtain fixture comprising spaced supports having outwardly extending guides and provided with outwardly bowed portions forming sockets, bearing brackets having arms fitting in and engaging the guides, and curtain pole brackets fitting in the sockets formed by the outwardly bowed portions of the supports. 105

2. A curtain fixture comprising a support having its ends bent outwardly to form guide flanges and bowed outwardly at an intermediate point to provide a socket, a bearing bracket adjustably supported by the guide flanges, and a curtain pole bracket having an arm to fit the said socket. 110

3. A curtain fixture comprising a support having its ends bent outwardly to form guide flanges and provided with aligned openings, said support being also bowed outwardly at 5 a point between the flanges, and the outwardly bowed portion being tapered downwardly to provide a wedge-shaped socket and to set the flanges at an inclination, and bearing brackets having notched arms fitting in

the openings of the guide flanges and engaging the latter.

In testimony, that I claim the foregoing as my own, I have hereto affixed my signature in the presence of two witnesses.

WILLIAM R. EVANS.
